UNITED STATES PATENT OFFICE.

JAMES A. MALONE, OF GRAYSON, KENTUCKY.

AMALGAMATOR.

1,317,984.

Specification of Letters Patent.

Patented Oct. 7, 1919.

Application filed August 22, 1917. Serial No. 187,692.

To all whom it may concern:

Be it known that I, JAMES A. MALONE, a citizen of the United States, residing at Grayson, in the county of Carter and State 5 of Kentucky, have invented certain new and useful Improvements in Amalgamators, of which the following is a specification.

This invention relates to amalgamators, and one of the objects is to provide a device 10 of the class described, or of such characteristics that the precious metals may be efficiently recovered from their ores, either with, or without subjecting the ores to an electrolytic action.

15 Another object of the invention is to provide means, whereby some of the metals may be recovered upon the initial introduction of the ores into the apparatus, and the remainder recovered through the agitation 20 of the crushed ores, sands or clays in the presence of a material having an affinity therefor, for example, mercury.

Other objects and advantages of the invention will be referred to hereinafter, it 25 being understood that changes in form, proportion and minor details of construction may be resorted to without departing from the spirit of the invention or sacrificing any of its advantages.

30 In the drawings:—

Figure 1 is a vertical longitudinal sectional view through an amalgamator constructed in accordance with my invention; and

35 Fig. 2 is a view partly in elevation, and partly in section, the section being taken on the line 2—2 of Fig. 1.

For the purpose of illustration, I have shown the amalgamator as consisting of a 40 receptacle 5, having an inlet 6 and an outlet or overflow 7. The top of the receptacle is closed by a cover 8 removably secured to the receptacle by the fastening devices 9. The inlet 6 which is located adjacent to the bottom of the receptacle 5 communicates with a supply chamber 10 at one end of the receptacle and in which is a rotatable cylinder 11 fixed on a shaft 12 extending through the sides of said chamber 10 and on one end of which is a pulley 13. The cylinder 11 is 45 preferably formed of copper or similar material and immediately beneath the same is a scraper 14, whereby any adhering particles on said cylinder may be removed from the surface of the cylinder during its rotation. In the throat 15 of the supply cham-

ber 10 is a spring-pressed yielding gate 16, the lower curved edge portion 17 of which at least, consists of material adapted to act as a conductor of electricity and said edge 60 portion 8 is in electrical communication with the binding post 18 in the upper wall of the chamber 10, so that the gate may form one of the anodes of the amalgamator. The cathode connection is shown at 19. The 65 floor 21 of receptacle 5 has spaced a short distance therefrom, a screen 22 which may be a perforate plate or a screen of some reticulated material and between the screen 22 and floor 1, I prefer to introduce a suitable medium 23, for example, mercury having an affinity for precious metals. The trough 24 in the floor 21 with its valved outlet 25 constitutes a flow-off or drain for the mercury, and 26 is a liquid drain for the 75 receptacle 5.

Journalized in the vertical bearing 27 on the floor 21 of the receptacle 5, and in the bearing 28 on the cover 8, is a shaft 29 carrying an agitator consisting of the cross 80 bars 30 and 31 and the vertical bars 32 of which there may be any suitable number. The shaft 29 carries at its upper end a beveled gear 33 meshing with a beveled gear 34 on a driven shaft 35 in the bearings 36 and 37 carried by the cover 8, and on one end of the shaft 35 is a power pulley 38, while on the other end is a pulley 39 having a belt connection with a pulley 13 on the shaft 12 of the cylinder 11. The cover 8 carries a 90 binding post 41 connected to a spring contact plate 42, the free end of which bears against the insulated contact ring 43 carried by the shaft 29 and leading from the ring 43 are the wires 44 traversing the vertical 95 bars 32, as best seen in Fig. 1. The bars 32 of the agitator thus constitute another anode of the amalgamator. The two binding posts 18 and 41 being connected to the same side of the exterior circuit.

When the parts are assembled, power may be communicated to the shaft 35 which will, in turn, rotate the shaft 29 to cause movement of the agitator within the receptacle 5 and through the belt 40 cause the rotation 105 of the cylinder 11.

As the material is fed through the throat 15, it will come in contact with the anode gate 16, the tension of which may be regulated and flow over the copper surface of 110 the cylinder 11. The cylinder is caused to revolve in the direction of the flow of pulp.

The lower portion of the cylinder slightly depresses the mercury or mercuric compound as it rotates. Any particles adhering thereto will be scraped off by the scraper 5 14, which also prevents an excess of pulp and mercury from entering behind the cylinder. The values raked off by the scraper are dropped into the mercury trough 24.

By the cathode connection 19 a suitable 10 voltage makes the amalgamated surface of cylinder 11, all the mercury, and the mercury cover 23, including the part of the latter extending under cylinder 11, the cathode pole, so that the current entering the anode 15 gate pole throws the values in the pulp, upon the amalgamated cylinder 11, whence as stated they are removed by the scraper and deposited in the mercury. The material then passes through the opening 6 into 20 the amalgamator chamber and is violently agitated by the agitator consisting of the shaft 29 and its bars 30, 31 and anode arms 32, the precious metals being collected by the mercurial bed and the waste passing out 25 through the over-flow 7. When it is desired to have access to the interior of the amalgamator for cleaning, or for other purposes, the fastening devices 9 may be released and the cover may be taken off carrying with it

the gearing and the agitator, inasmuch as 30 the agitator shaft 29 fits in step bearing 27. It will be apparent therefore that the device is simple in operation and easily accessible.

I claim:—

1. In a device of the class described the 35 combination of a feeding chamber having a cathode comprising a rotating feeding cylinder, an amalgamating chamber, having a cathode, an anode in the feeding chamber, and a rotating agitator-anode in the amalgamating chamber. 40

2. In a device such as set forth in claim 1, the cathode plate extending throughout 45 the bottoms of the feeding and amalgamating chambers.

3. In a device such as set forth in claim 1, the combination of the mercury trough and the scraper adjacent thereto and to the wall of the cylinder. 45

4. A device such as set forth in claim 1, 50 wherein the anode is in the form of a gate arranged in the feed passage adjacent to the cylinder.

The foregoing specification signed at Grayson, Kentucky, this fifth day of February, 1917. 55

JAMES A. MALONE.
